UNITED STATES PATENT OFFICE.

EMIL GMINDER, OF REUTLINGEN, GERMANY.

PROCESS AND APPARATUS FOR DEFIBERIZING PLANT PARTS AND CLEANING THE RECLAIMED FIBERS.

Application filed May 7, 1926, Serial No. 107,355, and in Germany May 8, 1925.

This invention relates particularly to mechanism for feeding fiber stalks, fibers, fibrous matter and the like, to mechanism operating to separate the fibers from the stalks or otherwise work upon, prepare, clean, card, loosen, or treat the fibers.

As one important feature of my invention I provide an improved means for delivering the material to the surface of a defiberizing drum, and in such a way that high speed and efficient operation are secured. It has heretofore been proposed to employ a pair of feeding rollers, but this has the disadvantage that the feeding point where the rollers engage with the material is comparatively far away from the drum, beater, or other working member. It has also been proposed to employ a single feed roller in connection with a guide member leading to the beater, but this necessitates comparatively slow speed and lower output.

By means of my invention the material is fed by a pair of rollers at the desired high speed, and is directly guided to the beater or other working member. Thus the material is under control at all times, and is brought into engagement with the striking tools or working member in such a way that a separation of the impurities from the fibers is effected by reason of the specific weight of the impurities, at the instant when the tool meets the material at the upper edge of the guide.

As another important feature of my invention I also construct and arrange the parts that the rotating drum which serves for defiberizing the material, also serves at another point on its periphery, for cleaning the fibers. The rotating drum is provided with pins or other striking parts which act to separate the fiber from the stalks, and in connection with this drum there is provided means which act to take off the fibers from the drum, separate impurities therefrom, and return the fibers to the drum where they are further cleaned. By means of my invention the necessary equipment for performing the desired operation is materially reduced in size, cost and number of parts, and is rendered far less cumbersome.

In the accompanying drawing I have illustrated one form of apparatus embodying

my invention, and which may be employed for carrying out my improved process.

The single figure of the drawing shows diagrammatically a transverse section at right angles to the axis of the several rotating parts.

In the construction illustrated there is employed a pair of feed rollers 1 and 2 which deliver to a drum 3. This drum is provided with pins or projections which constitute the working tools, and which strike or beat the material and separate the fibers from the stalks and other impurities. In order that the material may be properly brought into position to be operated upon by the drum 3, I space the feed roller 2 at a short distance away from the drum 3, and mount between the feed rollers and the drum a guide member 9. This guide member has a curved surface which is substantially parallel to but spaced from the upper roller 1. At one end of this curved face the member may be in direct contact with the lower feed roller 2, while at the opposite end of the face it is closely adjacent to the path of movement of the outer ends of the pins on the drum 3. The feed roller 2 preferably has its axis fixed and its surface may be smooth. The feed roller 1 may be so mounted as to permit of vertical movement and to accommodate variations in the thickness of the material passing between the feed rollers and between the guide member 9 and the upper feed roller 1.

The drum 3 rotates in a counter-clockwise direction, as indicated by the arrow, and the passage between the guide member 9 and the feed roller 1 extends upwardly at the side of the drum which moves downward in rotation. Thus the material is fed directly against the pins which strike it and separate the fibers from the stalk parts or other impurities. The side of the member 9 toward the drum 3 curves downwardly and away from the drum so that there is adequate intervening space through which the heavier parts of the material are thrown by centrifugal force, and below and beneath the upper inner working edge of the member 9. It will be noted that the material being fed is under control as it passes between the two feed rollers and continues under control as it moves along the space between

the member 9 and the upper feed roller. This upper feed roller may have either a smooth or a roughened surface, depending upon the character of the material to be operated on.

Directly beneath the drum 3 there is provided a drum 4 which may also have pins or other working tool parts thereon, for engaging with the fiber. The two drums 3 and 4 are so positioned in respect to each other that the pins of one pass closely adjacent to the pins of the other. Thus one drum serves to take off the material from the other, as the two drums rotate in the same direction. At 15 the lower side of the drum 3 below the member 9, there is provided a grating 5 leading to the take-off point 10, where the paths of movement of the pins on the two drums intersect. A similar grating 6 substantially 20 encircles the lower drum 4 to the opposite take-off point 11, and a grating 7 extends up along the side of the drum 3. Above the upper drum 3 is the conduit 8 where the wall leaves the path of the pins and the fibers 25 may be thrown off and leave this part of the machine.

As the heavy stalk parts are thrown down from the edge of the guide member 9, the eliminated particles may drop through the 30 grating 5, and as the fibers are transferred from the pins of the drums 3 to those of the pin 4, other particles of the liberated impurities may be separated from the fibers and pass through the grating 6. As the fibers 35 are transferred back to the drum 3 at the take-off point 11, further stalk particles and impurities may be separated and pass out through the grating 7.

It will thus be noted that the drum 3 40 serves not only for the breaking up of the stalks to defiberize them, but also acts as a part of the cleaning mechanism at the portion beyond the take-off point 11. The fibers are shifted twice, but only two drums are 45 employed. The gratings may be removable for cleaning purposes, and a section of the grating 11 may be hinged so that it may be opened to permit access to the lower drum without removing all of the grating.

Having thus described my invention, what 50 I claim as new and desire to secure by Letters Patent is:—

1. An apparatus for disintegrating and 55 cleaning fibrous material, including a drum, a pair of feed rollers and a guide member between one of said feed rollers and said drum, and having a surface substantially concentric with the other feed roller and a surface diverging from the surface of the 60 drum.

2. The combination with a rotatable drum 65 of a pair of feed rollers and a guide member, said guide member having a working edge closely adjacent to the periphery of said drum and to the periphery of one of said

feed rollers, one surface of said guide member extending downwardly substantially parallel to the surface of the last mentioned feed roller, and another surface extending downwardly from said working edge and diverging from the surface of said drum. 70

3. In combination a rotatable drum, a pair of feed rollers, one of said feed rollers being disposed closely adjacent to the periphery of said drum, and the other being disposed at a greater distance from said drum, and a guide member disposed between said last mentioned feed roller and said drum, and having a working edge adjacent to the line of tangency of the first mentioned feed roller 75 and said drum. 80

4. An apparatus for defiberizing plant stalks and subsequently cleaning the reclaimed fibers, including a drum having pins on the periphery thereof, a pair of feed rollers, a guide member cooperating with one feed roller to deliver the material to the surface of said drum, and a grating below said feed member and through which particles of fiber may pass. 85 90

5. An apparatus for defiberizing plant stalks and subsequently cleaning the reclaimed fibers, including a drum having pins on the periphery thereof, a pair of feed rollers, a guide member cooperating with one feed roller to deliver the material to the surface of said drum, and a second drum 95 also having pins on the periphery for taking off the fibers from the pins of the first mentioned drum. 100

6. An apparatus for defiberizing plant stalks and subsequently cleaning the reclaimed fibers, including a drum having pins on the periphery thereof, a pair of feed rollers, a guide member cooperating with one feed roller to deliver the material to the surface of said drum and firmly hold the portion of the material which is between the guide and the last mentioned feed roller for action thereon by said drum, and a second 105 drum also having pins on the periphery for taking off the fibers from the pins of the first mentioned drum, and a grating substantially encircling said second mentioned drum whereby the fibers are returned to the first mentioned drum and transferred to the latter. 110

7. An apparatus for defiberizing plant stalks and cleaning the fibers, including a pair of drums rotatable in the same direction and having fiber engaging pins upon the peripheries thereof the drums being so positioned in respect to each other that the pins of one drum remove the fiber from the pins of the other, means for delivering fibrous material to one of said drums, and a casing substantially encircling the other of said drums, whereby the fibers are transferred from the first mentioned drum to the second mentioned drum, and thereafter 115 120 125 130

re-transferred from the second mentioned drum to the first mentioned drum.

8. An apparatus for defiberizing plant stalks, including a drum having working tools upon the surface thereof for breaking and defiberizing the stalks, and a second drum having fiber carrying parts upon the periphery thereof, said drums being juxtaposed whereby two take-off points are formed, one for the transfer of fiber from the first mentioned drum to the second mentioned drum, and the other for transfer of fibers from the second mentioned drum to the first mentioned drum at the side opposite to the point of delivery of the fibrous material to said first mentioned drum.
9. A process for defiberizing plant stalks and subsequently cleaning the reclaimed fibers, which consists in defiberizing the material by the action of a drum, taking off

the fibers from said drum, cleaning them, and returning them to the drum at the side opposite to that at which the defiberizing action is effected.

10. A process of defiberizing plant stalks and subsequently cleaning the reclaimed fibers, which includes the step of delivering the material to be defiberized to a drum having peripherally disposed pins, defiberizing the material by the action of the drum at the point of delivery to the latter taking off the fibers from said pins by a second drum, and retransferring the fibers to the pins of the first mentioned drum at another point on the periphery of the latter.
